DISPENSING PACKAGE

Thomas Armstrong, Salem, Oreg., assignor to
Western Paper Converting Company, Salem,
Oreg.

Application December 30, 1935, Serial No. 56,787
Renewed February 7, 1939

1 Claim. (Cl. 229—51)

My present invention, in its broad aspect, has to do with improvements in packages for paper, as for instance ream packages for typewriter paper and the like, and more particularly it is my purpose to provide a package having means incorporated therein for readily and quickly removing an entire end of the package to expose the end edges and a part of the body of the contents whereby the contents (as for instance typewriter paper) may be withdrawn a portion at a time, as for instance sheet by sheet for use, while the rest of the contents of the package remains protected by the cover. Furthermore, it is my purpose to accomplish these ends in the simplest manner, so that the package may be opened without tools or the like. I provide what I shall hereinafter term a "tear-strip" or weakened band in the package (or rather the cover) which when removed detaches the end from the body, thereby exposing the ends of the sheets of paper which are the contents.

I am aware that dispensing packages having weakened portions adapted for ready removal have been provided in conjunction with paper articles specially folded, as for instance handkerchiefs and the like, but my invention differs from these in that the entire end of the package (or rather the cover) is adapted to be removed so that while the contents of the package is protected, the end and a part of the body of the content is exposed for withdrawal a portion at a time. Furthermore, in these prior art devices it is usually a dispensing opening which is formed, whereas in my package an entire end part of the cover of the package is removed.

In the drawing wherein like characters of reference are used to designate like or similar parts throughout the several views:—

Figure 1 is a perspective view of a package of typewriter paper formed in accordance with my invention,

Figure 2 is a perspective view of the end of the package showing the "tear-strip" partly detached, and

Figure 3 is a perspective view of the end of the package showing the end portion of the cover entirely removed to expose the contents of the package.

In the drawing, wherein I have shown a package of typewriter paper with a cover 1, having a top 2, bottom 3, ends 4 and sides 5; there is

provided a weakened band or "tear-strip" 6 adjacent one end thereof. This band is formed by spaced parallel lines of perforations 7 extending transversely completely about the cover. The cover has the usual meeting edges 8, so that the "tear-strip" 6 may be removed by slipping the finger nail under this edge and grasping the end of the tear-strip and pulling upon it until it is removed by severing along the perforated lines 7; and if desired the gum may be omitted under the end of the tear-strip so that the operation of removing it will be facilitated. The contents of the package is shown at 9 in Figure 3, in which figure the end portion of the cover, designated 10 is removed, the tear-strip having been detached and the end part removed to expose the ends and a part of the body of the sheets of paper forming the contents 9. The body 11 of the cover is not removed so that the body of the contents is protected, while the contents may be removed sheet by sheet as indicated in Figure 3. My invention is especially useful in offices where typewriter paper and the like may be used, and at the same time protected, by my present package.

While I have shown and described a special form of my invention, it is to be understood that changes in form, size, shape and details may be made provided they fall within the scope of what is claimed.

I claim:—

In a package cover of the type formed of single ply material the meeting edges of which overlap and are sealed together with adhesive, a pair of spaced, parallel weakened lines adjacent one end of the package cover formed by series of perforations therein forming a removable strip which may be torn out to sever the body of the cover from the end portion, the overlapping portion of the cover beneath the removable strip having no adhesive thereon and being unsealed so that a fingernail or instrument may be inserted thereunder to grasp the end of the strip to facilitate removing the same; the package cover designed to be used with the body portion forming a dispensing container for the contents while it is being used and withdrawn a part at a time, and the detached end, when removed serving to give access to the contents without removing or disturbing the body portion.

THOMAS ARMSTRONG. 50
